UNITED STATES PATENT OFFICE.

PETER C. MOSSNER, OF SAGINAW, MICHIGAN.

AUTOMATIC REVERSING DEVICE FOR WASHING-MACHINES.

1,392,961.

Specification of Letters Patent. Patented Oct. 11, 1921.

Application filed April 3, 1920. Serial No. 371,025.

To all whom it may concern:

Be it known that I, PETER C. MOSSNER, a citizen of the United States, residing at Saginaw, in the county of Saginaw and State 5 of Michigan, have invented certain new and useful Improvements in Automatic Reversing Devices for Washing-Machines; and I do hereby declare the following to be a full, clear, and exact description of the invention, 10 such as will enable others skilled in the art to which it appertains to make and use the same.

This invention relates to washing machines and the improvement pertains more 15 particularly to that class of washing machines employing a revolving drum in which the articles of clothing to be washed are placed, the drum being inclosed in an outer water-containing tub or casing.

20 My improvement pertains more particularly to certain improved means and devices for actuating the drum, the source of power being preferably an electric motor, or its equivalent, running continuously in one direction.

My improvement more specifically relates 25 to the driving or power-transmitting mechanism interposed between the revolving drum and the source of power, whereby the continuous rotation of the power-wheel imparts to the drum a continuous rotation for a specified number of turns in one direction, and then the reversing of the drum and its continuous rotation in the opposite direction 30 for a certain number of turns, thereby imparting to the drum rotations, first right-hand and then left-hand.

My improvement further includes means whereby, at each reversal of motion of the 40 drum, the drum is brought to rest at such a position that the opening of the drum, through which the articles to be washed are inserted, will always be at the top of travel of the drum, so that the opening is in convenient location for the insertion of the 45 articles to be washed and for the closing of the drum aperture.

With these and certain other objects in view, which will appear later in the specification, my invention comprises the devices described and claimed and the equivalents thereof.

My invention is illustrated in the accompanying drawings, in which Figure 1 is a 50 rear elevation of the completed washing machine with a wringer attached thereto.

Fig. 2 is a perspective detail of the principal parts of the reversing mechanism, showing the device by which the drum is brought to rest in the proper position. 60

Fig. 3 is an enlarged horizontal section of the machine, taken on the line 3—3 of Fig. 1.

Fig. 4 is an enlarged vertical section, broken away in part, the section being taken on the line 4—4 of Fig. 1. 65

As is clearly shown in the drawings, the machine consists in the usual tub or container 1 mounted in a suitable frame. In this tub is revolubly mounted a washing drum 2 having its periphery formed of slats 70 3 spaced apart in the usual manner.

4 is the drum-shaft, which may be mounted in suitable bearings carried by the tub 1. Upon the shaft 4 is a sprocket 5 carrying a chain 6, by means of which the drum is rotated. 75

To rotate the drum several revolutions, first in one direction and then in the opposite direction, I provide the mechanism shown in detail in Figs. 3 and 4, where 7 80 and 8 are sprocket wheels loosely carried by parallel shafts 9 and 10 revolubly mounted in suitable bearings on the frame of tub 1.

The chain 6 passes around sprocket 5 and also around sprockets 7 and 8. 85

Intermeshing gears 11 and 12 are fixed respectively to the shafts 9 and 10, one of these gears, as 12, being driven by a drive-gear 13, revolubly mounted on the drive-shaft 14, this shaft being carried by suitable 90 bearings supported by the frame of tub 1.

Fixed to one end of shaft 14 is a bevel gear 15, which meshes with beveled pinions 16, either of which is adapted to be clutched to a vertical shaft 17, which actuates 95 wringer 18. The opposite end of shaft 14 carries a worm-wheel 19, which is driven by a worm 20. Worm 20 is fixed to a shaft 21, and this shaft is alined with and normally connected to the shaft 22 of a motor 23, by 100 means of a friction-clutch 24.

When the motor is in operation, the worm 20, driven through the friction-clutch 24, actuates shaft 14 and gear 13, through the medium of a sliding clutch 25, which is 105 splined to shaft 14, one face of the clutch engaging a corresponding clutch-face on the drive-gear 13. The drive-gear 13 actuates the gears 11 and 12 and one only of the pair of sprockets 7 and 8. 110

It will be understood that the gears 11 and 12, being intermeshing gears, rotate in

opposite directions, as do also their shafts 9 and 10.

Either of the two sprockets, 7 or 8, may be locked to its shaft, the other sprocket of the 5 pair being loose on its shaft, by the following means:

Each sprocket is provided with a clutch-face adapted to be engaged by a clutch-member splined to the shaft. For example, in 10 Fig. 3, the face of clutch 26 is engaged in the gear 7, thus locking that gear to shaft 9, while clutch 27 is out of engagement with its gear 8.

To reverse the motion of chain 6, it is 15 only necessary to throw in clutch 27 and simultaneously disengage clutch 26. This is done by means of a rocking arm 28, which is shown in perspective in Fig. 2. This arm 28 carries two upwardly projecting pins, or 20 their equivalents, 29 and 30, the pin 29 actuating clutch 27 backward and forward along the shaft 19 and the pin 30 simultaneously actuating clutch 26 backward and forward along the shaft 9.

25 To oscillate the rocking arm 28, a horizontal projecting bar 31 is fixed to arm 28. This bar is adapted to be engaged by a lug, as 32, on chain 6. Thus, when the chain has traveled, say, to the right, a distance 30 equal to the length of the chain, the lug 32 engages the arm 31, throws out clutch 27 and throws in clutch 26, as shown in Fig. 3.

When the lug has struck the arm 31 and moved it to the right, thereby rocking the 35 arm 31 and throwing in clutch 27 while withdrawing clutch 26, the sprocket 8 thereupon becomes an actuating sprocket of the chain 6, and since the direction of revolution of sprocket 8 is opposite that of sprocket 7, the motion of the chain, and consequently the direction of rotation of drum 2 40 is reversed. The chain then continues to travel around in the opposite direction until lug 32 engages the bar 31 on the opposite 45 side, and the motion of the chain is again reversed.

It will be noted that a reversal of motion of the chain takes place once in each complete revolution of the chain, but since the 50 chain is of relatively great length as compared with the circumference of the sprocket 5, several revolutions, as three or more, of the drum will take place between the successive reversals of the chain. Thus the 55 chain will cause, say, three revolutions of the drum to the right and then three revolutions to the left.

The details of clutch 24 are not illustrated here, as any suitable friction clutch 60 may be employed for the purpose.

To stop the drum 2 at a predetermined position, as for example, the position when the opening in the drum, through which the clothes are inserted, is at the top, so that 65 the drum may be easily emptied or filled, I

provide the mechanism illustrated in detail in Fig. 2, in which 33 is a handle which rests upon a cam-shaped bracket 34 carried by the frame of the tub 1.

When handle 33 is turned, its downwardly 70 projecting end 35 raises and lowers a spring-arm 36, one end of which is fixed to the frame of the tub. On the outer end of this arm 36 rests one end 37 of a movable L-shaped bracket or latch, pivoted, as at 38, 75 to the frame of the machine, the upwardly projecting end of the latch being provided with a notch 39.

When the spring 36 is raised or lowered, 80 as indicated by the dotted lines in Fig. 2, the end of the L-shaped bracket is similarly raised or lowered and its notched end 39 is moved inwardly or outwardly, as indicated by the full and dotted lines in Fig. 2.

When the latch is in its upward position, 85 as shown by the dotted lines, it is out of engagement with the upwardly-projecting finger 40 of bar 31, but when handle 33 is in its lowered position, as indicated by full lines in Fig. 2, the notch 39 will receive the 90 projecting finger 40 when that finger reaches the middle of its travel, while being moved by the lug 32 on chain 6. Consequently, when the lug strikes the arm 31, if the handle 33 is in its lowered position, the 95 finger 40 will move to the central position of its travel and thereupon automatically become engaged by the notch 39 of the latch, thus locking the arm 31 in its central position, both clutches 26 and 27 being out of 100 engagement with the gears 7 and 8, stopping the drum in its proper position, with the opening uppermost, at the same time leaving the drum free to be turned by hand if desired, in the filling or emptying opera- 105

The opening of the drum, as above described is omitted from the drawings for the sake of clearness, it being understood that it can be provided with any suitable 110 cover and can be located at any desired part of the periphery of the drum, as is usual in this class of machines.

It will be understood that when the drum has been stopped, the finger 40, being held by the notch 39, and the clutches 26 and 27 both being out of engagement, it is desirable that means be provided for automatically throwing the clutch 26, or the clutch 27, as the case may be, into engagement when the drum is again started. Otherwise, the clutches would remain in their neutral position and the drum would not turn unless the rocking-arm 28 is moved either to the right or left when handle 33 120 is again shifted to start the machine.

To provide this automatic shifting of the arm 28, I provide springs 41 and 42, each of which is located at one side of the arm 31 and is adapted to be engaged by the lug 125 130

42 of chain 6 at the time the lug approaches the arm and throws the clutches out of action, in order to stop the machine. The spring being thus left under tension, it follows that when notch 39 is again drawn back to release the finger 40 by means of the handle 33, the spring, as 42 in Fig. 3, will automatically throw the bar 31 from its central position, thereby rocking the 10 arm 28 and throwing one of the clutches, as 26, into mesh with the clutch face of gear 7, thus positively starting the machine when handle 33 is moved to the position indicated in dotted lines in Fig. 2.

15 By the means above described, I have produced a washing machine of the revolving drum type of simple construction, effective in operation and not likely to get out of order. The parts are all so arranged as to be readily inclosed, and the mechanism, while being effective in operation, enables the drum to be automatically stopped at a predetermined position each time and to be again automatically started when the handle 25 is again moved.

Having thus described my invention, what

I claim and desire to secure by Letters Patent is:

In a washing machine, the combination of a revoluble drum having a shaft, a 30 sprocket on the shaft of said drum, a motor, and drum-actuating means comprising a pair of parallel shafts, a sprocket wheel 35 loose on each shaft, a clutch adapted to releasably secure each sprocket wheel to its shaft, intermeshing gears on said shafts, means for driving one of said gears from said motor, a drive chain engaging said drum shaft sprocket and said loose sprockets, a clutch-shifting device adapted to simultaneously actuate said clutches to engage one and disengage the other of said loose sprockets, and engaging means on said chain adapted to actuate said clutch-shifting device at each complete revolution of 40 said chain, whereby to impart to said drum a plurality of revolutions, first in one direction and then in the opposite direction, for the purposes set forth.

In testimony whereof, I affix my signature.

PETER C. MOSSNER.
